INTERNAL GRINDING MACHINE WITH
AUTOMATIC AIR GAUGE SIZING

William J. Bryant, Thor H. Ljunggren, and Willis F. Moore, Springfield, Vt., assignors to Bryant Chucking Grinder Company, Springfield, Vt., a corporation of Vermont

Application May 29, 1948, Serial No. 29,996

4 Claims. (Cl. 51—165)

1

This invention relates to internal grinding machines with automatic sizing mechanism, and has for an object to provide such a machine wherein in the final size control is produced by an air gage sizing mechanism, such a mechanism being capable of extremely high accuracy.

A further object is to embody the air gage in a plug gage mechanism which is periodically presented to the work during the finish grinding operation.

Still another object is to provide a plug air gage mechanism so constructed as to avoid violent indicator fluctuations with consequent liability to damage during the operation of the machine.

A further object is to provide mechanism by which the grinding operation is stopped and the wheel is retracted from the work as soon as the gage indicator shows that the desired finish hole size has been reached.

A further object is to provide for an automatic cycle of machine operations, the last of which comprises a finish grinding operation which is terminated automatically when the desired finished size as determined by the air gage has been reached.

Further objects and advantages will appear from the following description of an embodiment of the invention shown in the accompanying drawings in which

Figure 1 is a front elevation of an internal 30 grinding machine.

Figure 2 is a fragmentary vertical sectional view through the work spindle and the work and wheel carriage to a larger scale than Figure 1 and showing the carriage mounting and the gage stem and its actuating parts, the gage stem being shown as extended within the hole in the work.

Figures 3, 4 and 5 are detail sectional views to a larger scale showing successive relations between a work piece, a grinding wheel, and the air gage stem and related parts as the grinding and traverse of the work by the grinding wheel progresses, Figure 5 showing the parts after the hole has been ground to a size which permits the gage stem to enter it.

Figure 6 is a detail sectional view on line 6—6 of Figure 1.

Figure 7 is a diagrammatic sectional view of the air gage mechanism.

Figure 8 is a detail sectional view on line 8—8 of Figures 1 and 6.

Figure 9 is a detailed sectional view on line 9—9 of Figure 8.

Figure 10 is a diagrammatic view of the machine illustrating the cycle control mechanism

2

for gage controlled finish grinding, and either gage controlled or diamond sizing for rough grinding, the mechanism being set for gage controlled rough grinding.

5 Referring to the drawings, at 1 is indicated a machine base on which is mounted a traversing carriage 2 which supports a wheel head 3 carrying a grinding wheel spindle 4 upon the outer end of which is mounted a grinding wheel 5. The head 3 is mounted on the carriage 2 for adjustment backwardly and forwardly, being supported on ways 7 in which it is held by a retaining strip 8 (see Figure 2) held against a foot of the wheel head, as by screws 9. The traversing 10 carriage 2 carries a bar 10 extending in the direction of traverse, and the opposite ends of this bar are formed hollow as at 11 (see Figures 2 and 10), thereby providing hydraulic cylinders, within which extend plungers 12 having passages 15 13 therethrough with which communicate fluid pressure pipes 14 and 15. The plungers 12 are secured in caps 16, which, in turn, are secured to the bed 1 as by screws 17.

The bed is also provided with transverse ways 20 18 on which is mounted a transversely movable carriage 19 provided with ways 20 for the reception of a work head 21. The carriage 19 is shown as supported on rollers 22 and is guided along a guide strip 23 against opposite edges of which bear guide rollers 24 and 25. The specific mounting of this carriage 19 forms no part of the present invention, that shown being subject matter of Ljunggren application for patent Serial No. 680,502, filed June 29, 1946, for Carriage Mounting.

The work head 21 has journaled in bearings 28 a work spindle 29 having at its forward end a standard spindle nose 30 and at its rear end a driving pulley 55 by which the spindle may be rotated is keyed. To this nose is shown secured by bolts 31, a work-holding chuck 32 having a plurality of pivoted jaws 33 arranged in circular series about its axis and having fingers 34 at its forward end which engage the forward face 45 of a work piece W and hold it pressed back against stop pins 35 suitably carried by the chuck 32. This chuck per se also forms no part of the present invention, forming subject matter of the Ljunggren and Green Letters Patent No. 2,473,380, granted June 14, 1949, for Combination Diaphragm and Clamp Chuck. The jaws 33 are pivoted to a circular flange 40 extending outwardly from a sleeve 41 which is threaded to an actuating sleeve 42. By exerting 55 forward axial motion on the sleeve 42, the jaws

33 may be moved forwardly relative to the body of the chuck 32 to a point where they ride out from beneath a cam ring 43 so that springs 44 acting on the rear ends of the jaws 33 rock the jaws outwardly, freeing the work piece therefrom. The rear end of the sleeve 42 has journaled non-slidably thereon a ring 50 which is connected through a pin and slot connection at 51 with a lever 52 by the rocking of which the desired axial motion of the sleeve 42 may be effected, this sleeve 42 rotating with the spindle, being keyed thereto as at 53.

Slidable within the sleeve 42 is a tube 60, this tube constituting the stem of an air gage. At its forward end, as shown best on Figures 3, 4 and 5, it has a reduced diameter threaded portion 61 with which is engaged a work feeler head 62. This feeler head 62 has an enlarged diameter outer end portion 63 through which extends a plurality of radial passages 64 opening out from the periphery of the portion 63. The inner ends of these passages 64 lead from a chamber 65 opening to the interior of the tube 60. The feeler head 62 is of such an external diameter with respect to the desired finished size of the work that when it is engaged within the hole in the work, as shown in Figure 5, it permits discharge of air from the passages 64 past the head 63 and out from the hole in the work at a rate such that the air gage indicator will show the work to be of the desired finished size.

When the head 62 is out of the work, it is normally housed within a bored portion 70 of a sleeve 71 through which the stem 60 is slidable and which, in turn, is slidable axially within the sleeve 41. The counterbored hole 70 is of a size which receives the head 62, but is not the same as the desired finished size of the hole in the work so that the air gage indicator does not register correct hole size when the head 62 is within this counterbored portion.

A size gage of this general type is shown somewhat diagrammatically in Figure 7. The stem 60 is slidable at its rear end within a gland 75 from which it receives air under pressure from a pipe 76. This pipe 76 leads from the upper end of an indicator tube 77, the bore of which is tapered lengthwise, the amount of taper being much exaggerated in the drawings, the upper end of the tube 77 being of the larger diameter. The lower end of the tube 77 is connected through a pipe 78 with a reducing pressure valve 79 which receives compressed air from any suitable source through a pipe 80 and an air filter 81.

Within the indicator tube 77 there is an indicator bob 82 which floats in the air column and the height within this air column at which it rests is determined by the differences in pressure above and beneath it, which in turn, are determined by the freedom with which the air discharges through the passages 64, this, in turn, being responsive to the size of the hole in which the head 63 is positioned at any time. A very little difference in diameter of this hole causes a substantial change in the height position of the bob 82 within the indicator tube 77, thus giving a much magnified indication of hole size differences. A spring bumper 85 at the upper end of this tube takes the impact therefrom in case of a sudden drop in pressure in the pipe 76 which would cause the bob 82 to be blown violently upwardly. However, it is undesirable to permit too sudden fluctuations as the bob might be damaged thereby, and for this reason the sleeve 71 has been provided so that until

such time as the hole in the work piece W has been ground to sufficient size to permit the entry of the head 63 thereinto, it remains housed within the counterbored portion 70 of the sleeve 71, and when retracted from the hole it passes directly into this counterbored portion. This causes the bob 82 to remain suspended in the indicator tube 77, but when the head is in the sleeve, at a position different from that indicating correct hole size.

During at least the finish grinding portion of the machine cycle, the air gage is in operative condition so that as soon as correct finished size is reached, the gage will so indicate it and automatically separate the wheel from the work and stop the machine cycle. During this finish grinding, the stem 60 is periodically moved toward and from the work piece in time with the reciprocation of the grinding wheel, being moved toward the work as the grinding wheel is retracted and being retracted as the grinding wheel is being projected so as to be out of the way of the grinding wheel when it extends through the work hole, as in the position shown in Figure 3. The mechanism for so actuating the stem 60 is best illustrated in Figure 2. This stem 60, as well as all the other parts carried by the work spindle 29, rotates with the work spindle. The rear end portion of the stem 60 is journaled in bearings 90 in a casing 91 which is held against rotation, and to this casing 91 is slidably and pivotally connected the upper arm of a bell crank lever 92 fulcrumed on the shaft 63. The other arm 94 of this bell crank lever is connected through a link 95 to the upper end of a rod 96 guided for vertical motion through a bracket 97 secured to a fixed casing member 38 carried by the work head 21. The lower end of the rod 96 is provided with a head 99 which is engaged by an actuating rod 100 carried by one arm of a bell crank lever 101 and extended in the direction of motion of the carriage 19 so that the head 99 may bear thereon in all positions of the carriage 19. This bell crank lever is journaled on the pivot 102 carried by a bracket 103 secured to the bed 1. Another arm 104 of this bell crank lever 101 engages in the peripheral groove of a spool 105 carried by a rod 102, the inner end of which is in position to be struck by the end of the bar 10 when this bar approaches that end of its stroke in which the grinding wheel 5 extends furthest through the work (Figure 3), so that as the wheel moves to this extreme position, the rod 106 is moved to the left, rocking the bell crank lever 101 in a direction to lift the bar 99, which rocks the bell crank lever 94 in a direction to retract the stem 60 out of the way of the grinding wheel. The head 62 of this stem engaging the base of the counterbored portions 70 of the sleeve 71 also retracts the sleeve 71 out of contact with the work face against the action of the coil spring 110 which reacts between a head 111 of the sleeve 71 and a diaphragm portion 112 of the chuck 32. As the wheel is withdrawn by reverse motion of the bar 10, the rod 106 may follow it as far as permitted by a piston portion 120 thereon, riding to the end of a hydraulic cylinder 121, this piston 120 being carried by a sleeve 122 supporting and guiding the rod 106. This allows the rod 96 to drop and allows the spring 110 to press the sleeve 71 against the work piece as shown in Figure 4, and if the hole in the work is of sufficient size, allows the stem 60 to move still further in the same direction to project the head 62 into the work, as shown in Figure 5. When the stem is in

the work as shown in Figure 5, the position of the bob 82 of the air gage indicates the size of the hole and when this position is at the point corresponding to the desired hole size, the grinding is terminated in a manner which will later appear.

The mechanism for determining the cycle of operations of this machine, including the control of the final finish grinding operation by the air gage is a modification of that which forms subject matter in the application for patent by Thor H. Ljunggren filed October 5, 1946, Serial No. 701,443 for Internal Grinding Machine which is issued as Patent No. 2,502,862 on April 4, 1950. The mechanism for producing the relative feed between the work and the grinding wheel as illustrated herein is the same as that for this Ljunggren application and is shown best in Figures 6, 8, and 9.

The carriage 19 which supports the work holder is provided with a bracket 130 depending from its forward face and secured to the forward face of the carriage as by screws, one of which is shown at 131 in Figure 6. Journaled in this bracket is the forward end portion of a feed screw 132. This feed screw is threaded through a circular nut 133 which is journaled in an upwardly extending flange 134 of the frame 1. It is held against axial movement within a bushing 135 in this frame, and for this purpose it is provided with a circular end flange 136 between which and the bushing 135, a collar 137 is interposed, the inner end of the nut 133 being externally threaded for the reception of a nut 138 which may bear against a washer 139 interposed between it and the flange 134 and the bushing 135. The flange 136 is seated and secured in a socket in a gear 140 and by rotation of this gear 140 it is evident that the lead screw 132 may be moved axially without its rotation, imparting a corresponding motion to the carriage 19 and the work holder. Such rotation is made use of to effect the normal feed motion between the grinding wheel and the work as will later appear.

It is also evident that axial motion of the carriage may be produced by rotation of the feed screw 132 while the nut 133 is stationary. Such action is employed in accordance with the present construction for producing a slight feed motion of the carriage 19 in addition to that produced by rotation of the nut 133 to compensate for reduction of wheel size due to wear and truing. To this end, the outer end of the feed screw 132 has keyed thereto the hub 142 of a hand wheel 143, and secured to this hub is an annular worm gear 144 with which meshes a worm 145 fixed to a shaft 146. As shown in Figure 1, this shaft 146 has a knob 147 on one end which can be turned by the operator, and it is connected at its other end to a gear 148 which may be engaged by a vertical rack bar 149 carried at the upper end of a plunger 150 (see also Figure 10) of a hydraulic cylinder 159. This rack bar is normally held elevated as by a spring, but may be depressed against this spring, thus to turn the gear 148 when hydraulic fluid is introduced above it, as through a pipe 141. A suitable ratchet mechanism (not shown) is interposed between the gear 148 and the shaft 146 so that the lifting of the plunger 150 is ineffective to turn the shaft 146.

The gear 140 is rotated in order to produce the normal feed and retracting motions of the work carriage 19 by the rotation of a gear 150 meshing therewith, this gear being carried by a hub member 151 which also carries a gear portion 152 with

which meshes a rack bar 153. This rack bar 153, as shown diagrammatically in Figure 10, forms the piston rod for an hydraulic piston 154 riding in a hydraulic cylinder 155. When fluid pressure is introduced to the right hand end of this cylinder 155 as through the pipe 156, the gear 150 is rotated in a direction to feed the work relative to the wheel, while when it is moved in the reverse direction by fluid pressure introduced into the left hand end of the cylinder 155 through the pipe 157, the work is retracted relative to the wheel.

Means are provided by which, after the feed has been started and the work and grinding wheel fed toward each other from fully retracted position at relatively high speed to a point slightly before the wheel and work contact, the feed motion is slowed, and provision is made by which this slowing and the point at which it begins is independently adjustable during rough and finish grinding. This mechanism is shown best in Figures 8 and 9, and diagrammatically on Figure 10. The gear hub 151 has a forward extension 160 terminating in a reduced diameter portion 161.

Journaled on this portion 161 are a pair of arms 162 and 163 and keyed to the outer end of the extension 161 is a disk 164. This disk 164 is provided with a pair of arcuate slots 165 and 166, and the arms 162 and 163 have threaded thereinto the extremities of thumb screws 167 and 168 which extend through the slots 165 and 166, respectively, and by the tightening of which the arms 162 and 163 may be clamped in limited angular adjustment positions to the disk 164 and be caused to rock with the hub extension 160. Each of these arms 162 and 163 has secured to its rear face a rearwardly extending segmental arm 170 and 171, and each of these arms 170 and 171 is formed with a thin forward edge which may ride behind a corresponding switch-actuating roll 172 and 173. When these arms 170 or 171 engage the switch-actuating rolls 172 or 173, they close switches, which, as will later appear, interpose slowing mechanism in the feed controls, so that the speed of feed is reduced and independently for rough and finish grinding until such time as the feed motion is terminated. For the sake of clarity in the diagram (Figure 10), the elements 170 and 171 are not shown as arranged about the axis of the gear 150, but instead are shown as arranged about a second shaft in geared relation to the gear 150. Either arrangement, of course, may be employed.

With the mechanism herein shown, the feed is terminated for the finish grinding by the action of the air gage. For the rough grinding it may be terminated selectively either by the impingement of an extension of the piston rod 153 (see Figure 10) on a stop 175 carried by an axially movable bar 176, this being by diamond sizing, or it may be done by the action of the air gage. In the diagram of Figure 10 the parts are selectively adjusted for the control of both rough and finish grinding by the action of the gage. The bar 176 is normally pressed, as by a spring 177, into axial position to bring the stop 175 into alignment with the piston rod 153, and when in such alignment and when struck by the piston 153 and pressed axially, it closes a switch at 178 which acts to terminate the rough grinding. During finish grinding this bar 176 is placed in the position shown, by the introduction of hydraulic pressure beneath its lower end, so that the stop 175 is in inoperative position.

As hereinabove noted, the wheel supporting

carriage 2 is reciprocated by hydraulic means, this including the hydraulic cylinders formed in the end portions of the bar 10. This reciprocation is controlled by means shown somewhat diagrammatically in Figure 10. Movable with the carriage 2 are a series of depending dogs 200, 201, and 202. The dog 202 depends further than the others. The dog 200 is intermediate and the dog 201 is the shortest, and as the wheel carriage is reciprocated these dogs at the end of certain strokes act upon a follower roll 203 eccentrically carried by the upper end of a control element 204. This control element is rockably mounted and may take three different vertical positions. As shown it is in the highest of these positions where it is contacted on the inner end of its stroke by the dog 202 and on the outer end of its stroke by the dog 201. Such contact causes rocking of the member 204 and this is transmitted through a long gear 205 thereon and through a rack 206 to a reversing valve 207. This reversing valve has a pair of pressure lines 208 and 209 leading from a common line 210, deriving pressure from a pump 211 drawing a supply from a suitable tank 212. The pressure delivered by this pump is controlled by a pressure relief valve 213 which discharges back to the tank 212. In the position shown the valve 207 opens communication through the pipe 209 past the valve and the pipe 15 to the right hand cylinder 216, thus to drive the carriage 2 to the left, while the discharge takes place from the left hand cylinder through the pipe 14 past the valve 207, through the pipe 220, a valve chamber 221, past a cannelure 222 of this valve chamber 221, pipe 223, pipe 224 containing an adjustable throttle valve 225, pipe 226, and back to the tank 212. Also discharge may take place from the pipe 223 through the valve chamber 227 around a cannelure 228 of the valve 229, pipe 230 and throttle valve 231 to the pipe 226. The valves 225 and 231 are thus in parallel and the discharge from these two valves governs the traverse speed of bar 10 during the grinding phase of the work cycle and with valve 229 in lifted upper position shutting off pipe 230 from pipe 223, the lesser discharge through valve 225 governs the lesser speed of bar 10 during the dressing phase of the work cycle. When the traverse carriage 2 on the bar 10 reaches the point where the wheel is about to engage the work, a shoe 235 on the carriage engages and closes a switch 236, which closes a circuit from a lead 237 to leads 238 and 239 through a solenoid 249 to ground. Energization of this solenoid 249 lifts the valve 229, closing off the connection from the pipe 223 to pipe 230 so that discharge through the throttle valve 231 is cut off, requiring the full discharge to take place through the valve 225, which thus slows the traversing motion of the carriage so long as the lead 237 is supplied with energy by means which will later appear.

The length traverse determined by the dogs 201 and 202 is that of the grinding traverse. The control member 204 may be dropped to an intermediate position where it is contacted by the dog 202, but is not contacted by the dog 201. This permits an extended traverse until the dog 200 is contacted which is then effective to reverse the direction of traverse. This extended traverse takes place at the end of a rough grinding phase of the cycle and during this extended traverse the wheel may be trued as will later appear.

In the lowest position of the control member 204, the dog 202 is effective to produce reversal

of the direction of motion at the inner end of the stroke, but the dog 200 is ineffective to reverse the direction at the outer end of the stroke and the wheel carriage comes to rest against a suitable stop. This action takes place at the end of the grinding cycle, whereupon a finished work piece may be removed from the work holder and a new piece substituted. The operation of the machine is then resumed by the operator, rocking the control member 204 by hand to again produce its inward stroke.

The control member 204 is moved from one to another of its axial positions by hydraulic mechanism. To this end the member 204 beneath the cannelure 222 is formed with a socket within which rides the upper end of a piston 245 provided with a vent opening 246 therethrough. This member 245 has an enlarged diameter portion 247 which underlies the lower end of the member 204. When fluid pressure is admitted through the pipe 248 beneath the portion 247, the piston 245 is pushed upwardly to its upper limit as determined by impingement on the lower end of the casing of the valve 221 of a stop nut 250. When pressure is admitted between the portion 247 and the lower end of the member 204, as through the pipe 252, the member 204 is moved to its top position with an enlarged diameter portion 253 at the upper end of the casing 221. When pressure is discharged from both of these places, the member 204 is in its lowest position at the end of the grinding cycle, and when fluid pressure is admitted beneath the piston portion 247, and is discharged from between this and the lower end of the member 204, the member 204 is in its intermediate position for extended wheel truing traverse.

The mechanism for controlling admission of fluid under pressure to produce the various positions of the control member 204 and to control the traverse, feed and retracting motions between the wheel and the work, to control the operative or inoperative positioning of the stop 175, the wheel dressing mechanism and the dressing compensator, include electrically actuated hydraulic valves A, B, C, D, E, F, G, H, J, and K, and the supply of electric power to determine the positions of these valves is controlled by a single control mechanism comprising a shaft 260 having thereon a plurality of cams 261a, 261b, 261c, 261d, 261e, together with a rotary cam 262 and an actuating ratchet wheel 263.

The position of the parts shown in Figure 10 is that of the finish grinding cycle during the relatively slow feed portion prior to the termination of the cycle and the withdrawal of the wheel slide. In this position of the parts the hole in the work has been ground to rough size at which the feeler head 62 may enter the hole in the work, as shown in this figure, when the wheel is sufficiently withdrawn therefrom. Electrical energy is derived from the lines 300 and 301, the line 300 being the grounded side and the line 301 connected through leads 302 and 303 to a series of switches 304a, 304b, 304c, 304d, 304e and 304f, which are adapted to be closed at certain times by suitable cam projections on the cams 261a to 261e and 262. In the position shown, the switches 304d and 304e are closed. The closing of the switch 304d closes a circuit through the leads 305, 306 and the solenoid 307 to ground, lifting the valve D. This opens a communication from the pressure pipe 310 leading from the pump 211 through the pipe and passage 311 and 312, respectively, beneath

the element 176, thus lifting this element against the pressure of the spring 177 and moving the stop 175 out of alignment with the piston 153, thus conditioning the parts for determining the limit of grinding not by the extent of feed, but by the air gage, as will later appear.

The closing of the switch 304e closes a circuit through the leads 315, 316 through the solenoid 317 to ground, this lifting the valve E. The lifting of the valve E opens the pipe 157 from the feed cylinder 155 past the valve E through the pipe and passage 318 past the valve G through the pipe and passage 320, past the valve H, which is now lifted through closing of the cycle contact switch 304d, through the passage 321, the throttle valve 322, pipe and passage 323 and discharge pipe 324 which leads back to the discharge 226. The throttle valve 322 slows the feed to the desired point for finish grinding.

The valves G and H are both in lifted position, the valve G lifting solenoid 330 being energized from the lead 302 through the leads 326, 327, switch 328 which has been closed by finish feed cam 170, lead 329, solenoid 330 and to ground. The valve H is energized by the closing of the switch 304d, through the lead 305 and 306, the solenoid 335 to ground. This provides for slow feed, the discharge from the left hand of the feed cylinder 155 passing through pipe 157 past valve E, through pipe 318, past valves G and H, through throttle valve 322, and pipe 323 to discharge pipe 324.

The valve K is also in lifted position, this being accomplished by the closing of the switch 304e through the leads 305, 316, solenoid 337 to ground. This admits the pressure from the pressure line 310 past the lowered valve J and pipe 338 around the valve K and out through pipe 252 beneath the control member 204, and pressure is discharged through the pipe 248 from beneath the piston 247 through the pipe 248 around the valve J and through the pipe 340 to the discharge pipe 324. The control member 204 is thus in its lifted position for actuation by the dogs 201 and 202, which is thus in condition for the short grinding stroke of the carriage.

This condition takes place with the air gage stem entering the work on each retraction of the wheel therefrom until such time as the indicator bob 82 takes a position indicating the correct hole size at which it interrupts light from a light source 350 from falling upon a photo-electric cell 352. The light source 350 is energized from the secondary 353 of a transformer, the primary 354 of which is positioned across the lines 300 and 301 the current passing from the secondary 353 through lead 351, switch arm 356, lead 357, lamp 350, lead 358, back to the transformer secondary held closed by the energization of the relay 359 from lead 3590, switch 2000, lead 306 and closed cycle switch 304d and lead 303. As long as light passes from the source 350 to the photo-cell 352, current flows from rectifier 361 fed from the transformer primary 354 through a resistor 360 in series with the cell 352. This current is derived from the leads 300 and 301 through a conventional half wave rectifier, indicated at 361, from which leads 362 and 363 pass to the resistor 360 and to one terminal of the photo-cell 352, a lead 364 connecting the other side of the phototube to the resistor 360. While current so passes, a negative bias is obtained from the resistor 360 and passes through the leads 365, 366 and 367 to the grid of the gas filled "thyatron" tube 370, which blocks the anode

371 from passing current through the relay 372, one side of which is connected thereto through the lead 373. The other side is connected through lead 374 through normally closed switch 375 and lead 376 to a variable resistor 377, one end of which is connected through the lead 378 with the rectifier 355 which derives energy across the lines 309 and 301 from the transformer 380.

As soon as the bob 82 interrupts the light passing to the photo-cell, the photo-cell passes less current and after a small time delay effective to prevent momentary cutting off this light from actuating the mechanism, the negative bias on the grid of the "thyatron" 370 is reduced to a magnitude which allows passage of plate current and energizes the relay 372. This time delay, as shown, is afforded by the resistor 360 with capacity 3650 in parallel therewith. Closing of the relay 372 closes a switch 381, which through a lead 382 is connected to a solenoid 383. Energization of this solenoid 383 steps around the cycle change mechanism by acting on the ratchet wheel 263. This closes the switch 304f by the cam 262 to the lead 384 through the ratchet solenoid 383, impressing a secondary turning impulse to the shaft 260 and insuring a one-eighth rotation of this shaft at each actuation. This turn of the ratchet wheel opens the cycle switches 304d and 304e and closes the switch 304a, all the other cycle switches being open. The cycle mechanism is then in load angular position. Opening of the switch 304d deenergizes the relay 359 and extinguishes the lamp 350 since it allows the switch arm 356 to swing over, breaking contact with the lead 357 and making contact with the lead 385. The making of this contact with the lead 385 lights a second lamp 390 positioned beneath the lamp 350 and shielded therefrom by a partition 391 placed between them. The energization of the lamp 390 is from the transformer secondary 353 through lead 351, switch 356, lead 385, lamp 390, lead 358 and back to the transformer secondary 353. The lamp 390 shines through a translucent window in the sides of the gage tube 71 beneath the window through which the lamp 350 may shine and corresponds to a position of the bob 82 indicating a smaller size of the hole corresponding to the size at the end of the rough grinding operation.

Closing of the switch 304a by the cam 261a, the manually operated switch 3000 being in the full line position shown for complete size control by the air gage, closes a circuit from the lead 303 through switch 304a, lead 395, switch 3000 and lead 396 to the solenoid 392 and to ground. Energization of the solenoid 392 lifts the valve A and allows fluid under pressure from the pressure pipe 310 to flow through the pipe 393 to the right hand end of the cylinder 121, driving its piston 122 to the left so retracting the air gage from the work. Opening of the switch 304e deenergizes the solenoid 337, allowing the valve K to fall, which opens the pipe 252 to discharge. The valve 304c being open, valve J is also in the lowest position, opening pipe 248 to discharge. This allows the control member 204 to drop to its lowest position. Opening of the switch 304e deenergizes the solenoid 317, allowing the valves E and F to drop, opening up the left end of the feed cylinder 155 to discharge. The wheel carriage 2 thus fully retracts to loading position and the carriage 18 to fully retracted feed position, and since the member 204 is not automatically rocked to reverse the traverse, the wheel carriage stops in fully retracted position against a suitable stop. The closing

of the switch 304a also energizes the cycle start switch 410 through the lead 411 so that when the switch 410 is closed in the next cycle of operations, the cycle control mechanism will be stepped along by a further one-eighth turn.

To start the cycle, the operator rocks the member 204, which at this moment is in its lowermost vertical position, allowing discharge at the fast rate from left end cylinder 11, pipe 14, valve 207, pipe 220, cannelure 222, pipe 2230, pipe 226, to tank 212. The rocking of member 204 effects a reversal of the direction of traverse so that the wheel carriage starts at a fast speed rate toward the work, and as soon as the switch 410 is closed by contact with the inclined face of the dog 415 on the carriage, the ratchet solenoid 383 is energized through the lead 416 and the cycle control is stepped around to its second or rough grinding position in which switches 304b and 304e are closed, and switch 304a is opened. Closing of the switch 304e energizes the lead 316 and solenoid 317, lifting the valves E and F, opening fluid pressure to the right hand end of the feed cylinder and discharge from the left end, but under a fast rate. Energization of the lead 316 also energizes solenoid 337, lifting the valve K, which introduces fluid pressure beneath the valve 221, lifting the control member 204 to its highest position for working traverse.

Before the wheel contacts the work in feed direction, the cam 172 has been rotated sufficiently to close the switch 1720, which closes a circuit through the cycle switch 304b, leads 420 and 421, switch 1720, lead 329 and solenoid 330. This raises the valve G, which interposes the throttle valve 3220 in the discharge from the feed cylinder, the valve H being now lowered, cutting out the throttle valve 322.

The lower lamp 390 being now lighted and the gage being reciprocated in time with the wheel (the cylinder 121 being discharged through pipe 393 past lowered valve B), the gage enters the hole in the work before the completion of the rough grinding which is terminated when the bob 82 shuts off light to the cell 352 from the lamp 390. This, as before noted in connection with the finish grinding phase of the cycle, closes the switch 382 which steps the cycle control mechanism one-eighth of a turn to the dressing step of the cycle. In this step, switches 304a and 304c are closed. Closing of the switch 304a completes the circuit through the switch 3000 and lead 396 to the solenoid 392, lifting the valve A, introducing fluid pressure through the pipe 393 to the right of the gage, retracting cylinder 121 which retracts the gage. It also energizes the relay 412 through the lead 413 and opens the switch 375 in the anode circuit of the "thyatron" 370. It also energizes the lead 411 leading to the carriage operated switch 410, but on the retracting stroke of the carriage, the dog 415 yields so that the switch 410 is not operated. Closing of the switch 304c energizes the lead 425, which through lead 426, energizes the solenoid 402 and lifts the valve J. This introduces fluid pressure through the pipe 248 beneath the piston 245, and as the solenoid 331 has been deenergized, the pipe 252 is open to discharge so that the control member 204 takes its intermediate position, extending the traverse. When the carriage closes the switch 236, the solenoid 240 is energized from lead 303, closed switch 304c, lead 237, switch 236 and leads 238 and 239 and solenoid 240, lifting the valve 229, and slowing the traverse through the dressing throttle valve 225 only, and the valve B is lifted

due to the closing of the switch 236, placing the dressing tool into dressing position by fluid pressure passing through the pipe 230 into the dressing tool cylinder 431.

At this time, also, the feed is retracted from the work, valves E and F being both lowered because the cycle switch 304e is now open. This opens the left hand end of the feed cylinder 155 to pressure through the pipe 157 and the right end of this cylinder to discharge through the pipe 156, and as soon as the retraction is complete the double switch arm 397 closes connection from lead 401 to lead 403. This establishes a circuit from lead 303, closed cycle switch 304c, leads 425, and 426, 401, 403 and solenoid 404. This lifts valve C which allows fluid under pressure to pass this valve through pipe 141 into the compensator cylinder 159, which produces the additional feed increment which compensates for wheel wear and truing. When cycle switch 304c opens on the succeeding cycle control mechanism actuation, the valve C drops and passes discharge from the compensator cylinder, which returns the compensator feed to starting position. On the return traverse of the carriage, its stroke being reversed by turning of the member 204 by impingement by the dog 260, the switch 410 is closed by the dog 415, energizing the ratchet solenoid 383 and stepping the cycle mechanism a further one-eighth turn to finish grinding condition shown in Figure 10.

When diamond rough sizing rather than air gage rough sizing control is desired, the switches 2000 and 3000 are placed in their dotted line position. These switches are effective only in the rough grinding portion of the cycle when switch 304b and 304e are closed and the other cycle control switches are open. The closing of the switch 3000 to the switch 304b energizes the lead 396 and the solenoid 392, lifting the valve A, which causes fluid pressure to enter the right hand end of the cylinder 121 and retract the air gage. Closing the switch 304b also energizes the relay 412 and opens switch 375 and makes it possible for the "thyatron" tube to recover to the condition it had before the earlier impulse from a cell 352 caused the relay 372 to be energized. Closing the switch 2000 to the lead 302 energizes the relay 359 and causes the switch 356 to energize the finish grinding lamp 350. The valve D being lowered in this position of the cycle, the stop 175 is in line with the piston 153 so that rough grinding continues, first at a fast rate and then at a slower rate when the cam 171 closes the switch 1720, until the piston 153 strikes the stop 175 and closes the switch 178. This closes a circuit from the lead 302 through a time delay, lead 435, switch 178, leads 436, 4360, and 382 to the ratchet solenoid 383 which then acts to step the cycle control mechanism to its truing position. The cycle may thus selectively control the rough grinding either by the air gage or by so-called diamond sizing, the latter depending upon the feeding limit during the rough grinding operation.

From the foregoing description of certain embodiments of this invention, it should be evident to those skilled in the art that various changes and modifications might be made without departing from its spirit or scope.

We claim:

1. In combination in a hole grinding machine, an air gage having a size indicator and a tubular stem provided at one end with a work feeler portion of enlarged diameter, said feeler portion having an air discharge opening through its

periphery, a sleeve slidably surrounding said stem and having a counterbored end portion adapted at certain times to house said feeler portion and of an internal diameter slightly different from the desired finished size of a hole in a work piece so that when said feeler is within said sleeve said indicator is out of desired finish size indicating position, means supporting a work piece with a hole coaxial with said stem, a grinding wheel, means for rotating said wheel, means for relatively reciprocating said wheel and work axially, means for relatively feeding said wheel and work transverse to said axis, means acting in time with such reciprocation to press said stem and sleeve toward the work to enter the hole being ground therein when said hole becomes of sufficient size to receive said stem at which time said discharge orifice leaves said sleeve and enters the work whereupon said indicator indicates the hole size, a cycle control mechanism, and means actuated and controlled by said indicator when said indicator indicates the desired hole size to actuate said mechanism to effect the succeeding step in the cycle of the machine.

2. An internal grinding machine comprising a rotary work spindle, means for supporting work with a hole to be ground coaxial with said spindle, a rotary grinding wheel, means for relatively moving said spindle and wheel lengthwise of said axis to cause said wheel to traverse the work and to have an extended traverse to separate said wheel and work from each other, an air gage having a stem provided with a lateral orifice adapted to enter the hole in the work after such hole has been ground to nearly finished size, means acting in time with the relative traverse between the work and grinding wheel to present said stem to the work to enter therein when the hole is of sufficient size, a wheel truing device movable to and from a position to true the wheel during an extended traverse, means for producing a relative feed between the work and wheel laterally of the direction of traverse, a single control mechanism, means actuated at a predetermined feed position corresponding to termination of a rough grinding operation between said wheel and work to condition said control mechanism to effect extended traverse with wheel truing and then to resume grinding and feed, and means actuated by said air gage when said stem orifice enters the hole in the work and when said hole reaches desired finish size to effect extended traverse to separate the wheel from the work and to then terminate the cycle.

3. An internal grinding machine, comprising

a work holder, a grinding wheel, means for relatively moving said wheel and holder to cause said wheel to grind a hole in work carried by said holder, a hole size gage projectable into said hole when said hole is of sufficient size to admit it and including an upright column, means for alternately projecting and retracting said gage, a bob movable within said column and assuming a position therein corresponding to the hole size when said gage is in projected position, a cycle control mechanism determining a sequence of operations of a grinding cycle, and mechanism responsive to two positions of said bob in said column, in one position corresponding to roughing hole size and in the other position corresponding to finish hole size, to move said cycle control mechanism to the next controlling position in the cycle sequence.

4. An internal grinding machine, comprising a work holder, a grinding wheel, means for relatively moving said wheel and holder to cause said wheel to grind a hole in work carried by said holder, a hole size gage projectable into said hole when said hole is of sufficient size to admit it and including an upright column, means for alternately projecting and retracting said gage, a bob movable within said column and assuming a position therein corresponding to the hole size when said gage is in projected position, a cycle control mechanism determining a sequence of operations of a grinding cycle, means for projecting light beams across said column at either of two lengthwise positions one corresponding to a position of said bob corresponding to rough grinding size and the other to a position of said bob corresponding to finish size, and means responsive to the interruption of one and then the other of said light beams for moving said cycle control mechanism to the next following position.
